US0D1060228S

(12) **United States Design Patent** (10) Patent No.: **US D1,060,228 S**
(45) Date of Patent: ** Feb. 4, 2025

(54) **CHARGING PILE**

(71) Applicant: **NIO CO., LTD.**, Shanghai (CN)

(72) Inventors: **Xiang Zhang**, Shanghai (CN); **Maxime Pierre Pascal Leruyet**, Shanghai (CN); **Kechao Li**, Shanghai (CN); **Lang Zheng**, Shanghai (CN); **Iijian Xia**, Shanghai (CN)

(73) Assignee: **NIO CO., LTD.**, Shanghai (CN)

(**) Term: **15 Years**

(21) Appl. No.: **29/886,611**

(22) Filed: **Mar. 10, 2023**

Related U.S. Application Data

(62) Division of application No. 29/761,637, filed on Dec. 10, 2020, now Pat. No. Des. 995,445.

(57) **CLAIM**

The ornamental design for a charging pile, as shown and described.

DESCRIPTION

FIG. 1 is a perspective view of a socket for a charging gun of the charging pile;

FIG. 2 is a front view of the socket for the charging gun of the charging pile;

FIG. 3 is a left side view of the socket for the charging gun of the charging pile;

FIG. 4 is a right side view of the socket for the charging gun of the charging pile;

FIG. 5 is a top view of the socket for the charging gun of the charging pile; and,

FIG. 6 is a bottom view of the socket for the charging gun of the charging pile.

The broken lines shown in the drawings are for the purpose of illustrating portions of the charging pile that form no part of the claimed design.

1 Claim, 3 Drawing Sheets
